METALLURGICAL FURNACE

Leslie G. Jenness, Newark, N. J., assignor to Intermetal Corporation, New York, N. Y., a corporation of Delaware

Application July 11, 1934, Serial No. 734,566
Renewed October 13, 1937

10 Claims. (Cl. 263—26)

The present invention relates to improvements in metallurgical furnaces of the multiple-hearth type and has for a general object the provision of such a furnace which is readily constructed, 5 sturdy, and adapted for efficient use in a variety of processes for separating metals from ores and oxides.

More specific objects are the provisions of such a furnace featured by a furnace chamber having 10 a rabble assembly which is suspended from a gas-tight bearing in the top of the furnace chamber provided with rabble arms and rake blades of a simple and sturdy design allowing ready assembly from interchangeable parts in combination with 15 a gas-tight receiver at the bottom for receiving discharged material and a vapor condenser connected to the top of the furnace chamber; a gas-tight receiver for collecting reduced material having an agitator for intermingling it with oil, 20 which is of a simple and novel design and efficient in operation; a vapor condenser constructionally adapted for efficient use; an efficient charging device of simple and novel construction; and other features of construction which collectively contribute to simplicity and efficiency of operation of 25 the furnace.

Other objects of the invention will in part be obvious and will in part appear hereinafter.

The invention accordingly comprises the features of construction, combination of elements 30 and arrangement of parts, which will be exemplified in the construction hereinafter set forth and the scope of the invention will be indicated in the claims.

35 For a fuller understanding of the nature and objects of the invention reference should be had to the following detailed description taken in connection with the accompanying drawings, in which:

40 Fig. 1 is a top plan view of the metallurgical furnace of the present invention, with parts broken away;

Fig. 2 is a vertical section taken on line 2—2 of Fig. 1;

45 Fig. 3 is an enlarged horizontal section taken on line 3—3 of Fig. 2;

Fig. 4 is an enlarged horizontal section taken on line 4—4 of Fig. 2;

Fig. 5 is a vertical section with parts broken 50 away taken on line 5—5 of Fig. 1;

Fig. 6 is an enlarged vertical sectional view of the gas-tight shaft supporting bearing mounted in the top of the furnace proper;

Fig. 7 is an enlarged vertical sectional view of the guiding bearing for the rabble shaft;

Fig. 8 is an enlarged plan view with parts in section and parts broken away of a rabble arm and rakes assembled thereon;

Fig. 9 is a side view of the rabble arm and rakes assemblage shown in Fig. 8;

Fig. 10 is a plan view of the charging device and associated hopper;

Fig. 11 is an enlarged vertical section taken on line 11—11 of Fig. 10 and showing the device mounted in a portion of the wall of the furnace 10 chamber; and

Fig. 12 is a vertical section taken on line 12—12 of Fig. 11 with the furnace wall portion omitted.

The metallurgical furnace of the present invention is intended primarily for processing ores 15 of metals and oxides of metals in powdered form by treatment with gases at elevated temperatures. Two particular processes for which it is applicable are (1) the reduction of metal oxides by hydrogen; and (2) the separation of metals from ores by chloridizing the metal with sulphur dichloride and chlorine, vaporizing the metal chloride and collecting it by condensation.

The furnace proper consists of a vertical cylinder containing a series of horizontal soles, 20 alternate soles being apertured at the center and at the periphery for passage of material with the peripherally apertured soles provided with central apertures to receive a shaft. The soles are supported on brackets on the inside walls of the cylinder with connections which prevent rotation of the soles but permit relative movement with the cylinder walls so as to obviate buckling due to expansion at high temperature. A rotating shaft is suspended centrally from the upper end 25 of the furnace and guided by a bearing near the lower end. This shaft carries radial rabble arms, one set of rabble arms above each sole. The rabble arms carry rabble rake blades obliquely disposed which just clear the soles. The disposition 30 of the rabble rake blades on the rabble arms is such that the set of blades immediately above the centrally apertured sole will gradually work a charge of powdered material from the outside of the sole to the central aperture, and the set of 35 rake blades immediately above a peripherally apertured sole will gradually work a charge of powdered material from the center to the periphery.

The soles thus act as baffles and the rabble rake 40 blades move the powdered charge from the outside of one sole to its central aperture where it drops down on to the succeeding sole below and is moved by the next set of rake blades to the periphery of the last mentioned sole where it

drops down on to the sole below. Thus the rapidity with which the charge of powdered material is moved from the top to the bottom of the furnace can be regulated by the speed at which the vertical shaft is rotated and by the angle, or angles, at which the rake blades are disposed with respect to the rabble arms and by the clearance between the rake blades and the soles.

The powdered material is charged into the furnace near the top of the cylinder wall, just above the uppermost sole. Charging is accomplished through a worm tube led into the side of the cylinder on a downward slope. The powdered material is supplied to the worm tube from a hopper, the top of which can be closed gas-tight if desired. However, it has been found that usually the body of powdered material in the tube and hopper will serve as an efficient gas-tight seal. To overcome any caking at the bottom of the hopper, a pair of shafts are provided with staggered pins and the rotation of these shafts in opposite directions and passing of the pins insure the feeding of loose material to the worm. The rate of charging the powdered material into the furnace is governed by the rate at which the worm is driven.

To insure tightness at the bearing of the vertical shaft a ball and socket suspension is provided. The weight of the shaft and its rabble arms and rake blades insures a good seat of the ball in its socket and prevents the escape of any gas at this point. The lower bearing does not carry any weight but merely guides the lower end of the vertical shaft.

Electrical resistance heating elements are provided around the cylindrical wall of the furnace and so arranged that heat may be applied or cut off at all levels, or at any desired level. Outside the heating elements, suitable heat insulation is provided. Pyrometer tubes inserted in the vertical wall enable the inside temperature of the furnace to be determined at any desired level.

Means are provided for admitting gas, or gases, or gas generating liquids at or near the bottom of the furnace chamber. A gas-tight vapor condenser is connected to the top of the furnace chamber for receiving gaseous or vaporous material discharged from the furnace chamber and a gas-tight receiver is provided for hot powdered material discharged at the bottom of the furnace chamber. The particular construction of the gas-tight vapor condenser and the receiver for powdered material depends upon the particular use to which the furnace is to be put.

When the furnace is used to reduce a metallic oxide by hydrogen the valuable product is the reduced metal which is discharged at the bottom of the furnace chamber and the waste product is water vapor which passes out at the top. To collect the powdered metal, a receiver, consisting of a mixing chamber, preferably a horizontal cylinder, and an agitator, is secured to the under side of the furnace chamber with a gas-tight joint and the cylinder is partly filled with oil into which the metal powder falls and by which it is cooled. The agitator, preferably a central horizontal shaft with a discontinuous worm, keeps the metal powder and oil in motion toward one end of the cylinder. As the oil will flow back more easily than the metal powder a sludge is produced at one end of the cylinder with relatively clean oil at the other end and in the middle to receive new additions of metal powder. The cylinder is provided with means for admitting hydrogen gas, with means for supply-

ing oil as needed and with means for removing the sludge of oil and metal powder when desired.

To take care of the waste material issuing at the top of the furnace chamber a vapor condenser consisting of another chamber, preferably cylindrical, is provided into which the water vapor and any unused hydrogen is received. Cooling coils located in the ends of this cylinder condense the water vapor which is allowed to run off by gravity through suitable water seals or traps. The condensation of the water vapor in this cylinder tends to facilitate the rise of the gases through the furnace by the creation of a greater or less degree of vacuum. Condensed water is prevented from getting back into the furnace by a baffle or suitable elevation around the opening from the furnace into the cylinder.

An outlet is also provided for excess hydrogen which can be piped out-doors or to some place where it will not create a dangerous condition, or can be purified and recycled.

When the furnace is used for separating metals from ores by a chloridizing and vaporizing process the desired metal compounds pass out at the top of the furnace chamber in the form of vaporized metal chlorides and the waste material from the ore passes out at the bottom of the furnace chamber in the form of a powder. For such use, the furnace is provided with any suitable gas-tight receiver to receive the powder discharged at the bottom, connected by a gas-tight joint with the bottom opening. Sulphur dichloride which is a liquid is introduced through the side wall of the furnace near the bottom and is vaporized by the heat in the furnace. The introduction may be made at one or more levels as demanded by the process being carried on in the furnace. Chlorine, which is a gas at ordinary temperature, is also introduced through the side wall of the furnace preferably with the sulphur dichloride.

The vaporized metal chlorides which result from the reaction pass out at the top of the furnace chamber and are condensed in a vapor condenser consisting of suitable gas-tight receivers by lowering the temperatures. Such a process may be carried out in this furnace as selective separations by control of the furnace temperature so as to chloridize and vaporize one metal from the ore at a time, or they may be carried out at a temperature sufficiently high to chloridize and vaporize two or more metals in the ore and the resultant metal chlorides separated by fractional condensation.

Referring to the drawings for a more detailed description of the invention like numerals refer to like parts throughout:

A vertically disposed furnace chamber consisting of a cylinder 13 is provided with a flange 14 at the top to which is bolted a top plate 15, a flange 16 at the bottom to which is bolted a bottom plate 17 provided with a discharge passage 18 having a flange 19 to which is bolted in a gas-tight manner the inlet opening of a gas-tight receiver which may be a mixing chamber 20, hereinafter more fully described, or a gas-tight receptacle as required by the use to which the metallurgical furnace is put. Around the walls of the furnace are disposed series of electrical heating elements 21-21 overlaid by a layer of insulating material 22 and through the walls of the furnace at various levels are positioned pyrometer tubes 23-23 whereby the heat in any particular zone in the furnace may be determined. The heating elements 21-21 are adapt-

ed to be operated in a variety of combinations so that the heating in all zones may be controlled.

Within the furnace chamber 13 are located a series of horizontal soles 24—24 and 25—25 alternately arranged, the soles 24—24 being apertured at the center and the soles 25—25 being apertured at the periphery thereof for passage of material with the soles 25—25 additionally apertured at the center for receiving a shaft, as is more particularly shown in Figs. 3 and 4. A baffle plate 26 is mounted above the upper sole 24 and is of similar construction.

A verticle shaft 27 is suspended centrally from the top of the furnace by a gas-tight bearing assembly 28 and guided in a bearing 29 in the lower sole 25. Upon the vertical shaft 27 are mounted a series of collars 30—30, each collar being located above one of the soles 24—24 and 25—25 and consisting of at least two sections 31, 20 31 bolted together whereby the collar may be clamped upon the shaft 27 in any desired position.

A rabble arm 32 is mounted upon each section 31, preferably being threaded into a tapped hole as shown in Fig. 8. A sleeve 33 is mounted upon the rabble arm 32 and has a face of one end abutting a shoulder 34 on the section 31. The face of the other end of the sleeve 33 is disposed at an oblique angle to the axis of the rabble arm 32, preferably at an angle of 45°. A rabble plate or rake blade 35 is provided with an aperture the axis of which is disposed at an oblique angle to the axis of the rabble arm 32 preferably at an angle of 45° and is mounted upon the rabble arm 32 to abut against the face of the end of the sleeve 33. A similar rabble plate or rake blade 36 is mounted in a similar manner upon the rabble arm 32 and spaced from the rake blade 35 by a spacing sleeve 37 having the faces of the ends thereof disposed at angles to abut against the adjacent faces of the rake blades 35 and 36. An additional rabble plate or rake blade 38 is mounted upon the rabble arm 32 in a similar manner. The rake blade 38 is similar in all respects to the rake blades 35 and 36 except that it is of greater width to provide a leading edge as depicted in Fig. 8. A spacing sleeve 39, similar to the spacing sleeve 37, is mounted between the rake blades 36 and 38. To secure the assemblage in position upon the rabble arm 32 an additional sleeve 40 is provided having the face of one end engaging the adjacent face of the rake blade 38 and the other end engaged by a head 41 of a bolt 42 threaded into a tapped hole in the outer end of the rabble arm 32.

Such structure allows ready assembling of the rabble plates or rake blades on the rabble arms 32 and any desired arrangement, as illustrated in Figs. 3 and 4 and illustrated in Fig. 8 in full and dot-dash lines, whereby ore material may be worked across the soles either toward the centers thereof or toward the peripheries thereof at any desired speed. If desired, a spacing sleeve 43 having the faces of the ends thereof disposed at right angles to each other and at substantially 45° to the axis of the rabble arm 32 may be substituted for the spacing sleeve 39 between rake blades 36 and 38 on one of the rabble arms 32—32 in the rabble assemblages above soles 25—25 whereby the rake blade 38 in each assemblage may operate in a more efficient manner in directing the ore material through the peripheral apertures in the sole 25 and insuring removal of powdered material from the sole supporting

structure adjacent the walls of the furnace chamber.

Opposite each of the soles 25—25 in the wall of the furnace chamber is preferably provided an inspection hole, not shown, suitably closed by a gas-tight cover to allow ready inspection and adjustment of the rabble rake assemblages above the soles 24 and 25.

The soles 24—24 are made of a diameter slightly smaller than the inside diameter of the furnace chamber and supported upon suitable supports 44—44 to permit relative movement with the chamber walls so as to obviate buckling due to expansion at high temperatures, while preventing rotation of the soles. Similar provisions are made for mounting the soles 25—25.

The powdered ore material is charged into the furnace near the top of the furnace chamber just above the top sole 24 and below the baffle plate 26 by a charging device 45 consisting of a worm tube 46 having an end 47 arranged to project through the wall 13 and provided with a mounting flange 48. The worm tube 46 is inclined downwardly as shown to facilitate travel of the powdered ore material. In the upper end of the worm tube 46 is seated a bearing structure 49 having a sealing ring 50 threaded therein. A feeding worm 51 is positioned within the worm tube 46 and a shaft 52 for the feeding worm projects through the sealing ring 50 and bearing structure 49 and has a bevel gear 53 keyed to the end thereof. A bracket 54 rotatably supports a bevel gear 55 meshed with the bevel gear 53 and a spur gear 56 keyed with the bevel gear 55.

A casting 57 having a passage 58 is mounted vertically upon the worm tube 46 with the passage 58 aligned with an aperture in the worm tube 46 as shown. A hopper 59 is mounted upon the casting 57 and, if desired, may be provided with a cover to insure gas-tightness.

A pair of shafts 60, 60 are horizontally disposed side by side within the passage 58 with the inner ends seated in supporting recesses and the outer ends reduced and rotatably mounted in bearing structures 61, 61 supported by the casting 57. Meshed pinions 62, 62 are keyed to the ends of the shafts 60, 60. A plurality of pins 63—63 are mounted on each of the shafts 60, 60 of a length sufficient just to clear the adjacent shaft and arranged on both shafts 60, 60 in alternate fashion so that they will pass each other in rotation of the shafts 60, 60. The pinions 62, 62 being in mesh will rotate the shafts 60, 60 in opposite directions so that when operated with the pins 63—63 moving downwardly between the shafts 60, 60 the powdered ore material in the bottom of the hopper will be agitated and fed into the worm tube 46.

A rotatable shaft 64 is mounted on one side of the casting 57 and is provided with a spur gear 65 keyed thereto in mesh with spur gear 56 and a spur gear 66 keyed thereto in mesh with one of the pinions 62, 62. Any suitable means are provided for rotating the shaft 64 so that the feeding worm 51 and the agitating shafts 60, 60 may be simultaneously operated.

The rabble shaft 27, as has been previously indicated, is supported from the top of the furnace chamber by a gas-tight bearing structure 28. This bearing structure consists of a collar 67 mounted upon the top plate 15, preferably welded thereto. A centrally disposed hole in the collar 67 is aligned with a hole in the plate 15 and internally threaded at 68 as shown in Fig. 6. The

collar 67 is also provided with a recess 69 in which is seated a gasket 70 of suitable material. A socket member 71 is mounted upon the collar 67 provided with a threaded neck 72 threaded into the threaded aligned holes in the collar 67 and the plate 15 with the gasket 60 acting as an efficient seal between the collar 67 and a portion of the socket 71. A collar 73 is mounted, preferably threaded, upon the rabble shaft 27. The collar 73 is provided with a lower crowned supporting bearing surface 74, preferably spherical, and the socket member 71 is provided with a mating bearing surface as shown. The entire rabble assemblage is thus supported from the top 15 of the furnace chamber by the bearing structure 28 and the weight of the rabble assemblage causes the bearing to seat within the socket in a gas-tight manner. However, in order to augment the gas-tightness of the bearing the collar 73 is provided with a threaded neck 75 engaged by an internally threaded ring 76 recessed at 77 to confine a gasket 78 between the wall of the socket and the ring 76.

When the metallurgical furnace is used for the reduction of metal oxides by hydrogen a gas-tight receiver comprising the mixing chamber 20 is bolted to flange 18 in a gas-tight manner with the passage 18 aligned with an inlet passage 19 in the top of a horizontally disposed cylinder 80 and adjacent one end thereof. The horizontally disposed cylinder 80 is provided at one end with a closure plate 81 having on the inner face thereof a supporting bearing 82 and at the other end with a closure plate 83 having a bearing structure 84 mounted therein. A rotatable shaft 85 is mounted in the bearings 82 and 84 with one end thereof projecting through the bearing structure 84 for application of motive power. Upon the shaft 85 are mounted a series of angularly disposed blades 86-86 to form a discontinuous worm. At the inlet end of the chamber 80 is provided a hydrogen inlet 87, and at the other end of the chamber 80, hereinafter called the discharge end, is provided a suitable discharge conduit 88 and an oil inlet 89, the oil inlet preferably being located in the top of the cylinder 80, as shown, for gravity flow of oil. The blades 86 are rotated by the shaft 85 in a direction so that reduced ore material discharged from the furnace chamber into the mixing chamber will be worked toward the discharge conduit 88. The discharge conduit 88 may be connected by a suitable conduit 90 to a pump or other means to draw off a sludge of oil and reduced ore material when desired.

In reducing metal oxides with hydrogen, means are provided for carrying away and condensing the water vapor formed by combining the hydrogen with oxygen from the ore, and for carrying away excess hydrogen. A vapor condenser 91 is provided for this purpose consisting of a horizontally disposed cylinder 92 closed at the ends thereof by plates 93, 93 and connected by a passage 94 with an opening in the plate 15 at the top of the furnace chamber. Around the passage 94 is provided a suitable baffle 95 to prevent back-flow into the furnace chamber of condensed water vapor. Suitable cooling coils 96, 96 are provided in the ends of the condenser. Water is carried off from the condenser by suitable conduits 97, 97 provided with pot heads 98, 98 each of which consists of a container into which the conduit 97 projects below an outlet 99. Conduits 100, 100 are also provided in the top of the condenser cylinder

92 to carry off excess hydrogen. Each of the conduits 100, 100 is also provided with a pot heat 101 to act as a water seal.

In operation powdered ore material is placed within the hopper 59 which, if desired, may be supplied with a gas-tight cover. However, the mass of powdered material in the hopper acts as an efficient gas-tight seal. The shaft 64 is rotated so that the pins 63-63 on the shafts 60, 60 will agitate the powdered ore material to prevent caking and to insure positive feeding of the ore material to the feeding worm 51 which is likewise operated by rotation of the shaft 64. Powdered ore material drops down upon the upper sole 24. The baffle plate 26 being disposed thereabove prevents dust and the like from being carried off with the gaseous or vaporous material discharged from the top of the furnace chamber. The rabble shaft 27 is rotated to the right so that the rake blades above the upper sole 24 will work the ore material toward the aperture in the center thereof. The ore material then drops down upon the sole 25 therebelow and is worked by the rake blades toward the apertures in the periphery thereof. The rapidity with which the charge of powdered material is moved from the top to the bottom of the furnace chamber is regulated by the speed with which the rabble shaft is rotated, by the angle, or angles, at which the rake blades are disposed with respect to the rabble arm, and by the clearance between the rake blades and the soles.

When the metallurgical furnace is used to reduce metal oxides by hydrogen, the hydrogen is introduced through the inlet 87 in the mixing chamber 20 and rises through the outlet 18 in the furnace chamber up past the charge of powdered material as the latter is gradually worked down through the furnace chamber. The waste material consists of water vapor and excess hydrogen which will discharge from the top of the furnace chamber into the vapor condenser 91 where the water vapor is condensed and discharged through the conduits 97, 97 and the excess hydrogen is discharged through the conduits 100, 100 to be carried away as waste material or to be purified and recycled. Oil is introduced into the mixing chamber 20 through the inlet 89 and reduced ore material is discharged from the furnace chamber through the passage 18 into the mixing chamber 20. The shaft 85 is rotated to the right so that the powdered ore material and oil will be thoroughly mixed together to form a sludge which is gradually worked toward the discharge conduit 88 through which it may be removed as desired by any suitable means such as a pump.

When the metallurgical furnace is used for the separation of metals from ores by chloridizing the metal with sulphur dichloride and chlorine, waste material in powdered form is discharged through the passage 18 into a gas-tight receiver of any suitable construction connected by a gas-tight joint to the flange 19 and the desired metal compounds pass out at the top of the furnace chamber in the form of vaporized metal chlorides into a vapor condenser. Selective separations may be carried out by control of the furnace temperature so as to chloridize and vaporize one metal from the ore at a time and condensation of the vapor in a gas-tight container by lowering the temperature, or by control of the furnace temperature sufficiently high to chloridize and vaporize two or more metals in the ore and fractional condensation in successive gas-tight containers by lowering the temperature to a predetermined

degree in each of the containers. Sulphur dichloride, which is a liquid at ordinary temperatures, and chlorine which is a gas, are introduced preferably together through the side wall of the furnace near the bottom of the furnace chamber at one or more levels as demanded by the process being carried out.

It will thus be seen that the present invention attains in an efficient manner the objects set forth above. Since certain changes may be made in the above construction and different embodiments of the invention could be made without departing from the scope thereof, it is intended that all matter contained in the above description or shown in the accompanying drawings shall be interpreted as illustrative and not in a limiting sense.

Having described my invention, what I claim as new and desire to secure by Letters Patent is:

1. In a metallurgical furnace the combination with a gas-tight furnace chamber, of a rabble assemblage including a vertical rabble shaft having an enlarged portion provided with a crowned supporting bearing surface, a socket in the top 25 of said chamber to receive said enlarged portion and having a mating bearing surface, and means sealing said enlarged portion in said socket in a gas-tight manner.

2. In a metallurgical furnace the combination with a gas-tight furnace chamber, of a rabble assemblage including a vertical rabble shaft, a collar on said shaft having a lower spherical bearing surface, a socket in the top of said chamber to receive said collar and having a mating bearing 35 surface, and sealing means between said collar and said socket.

3. In a metallurgical furnace the combination with a gas-tight furnace chamber, of a rabble assemblage including a vertical rabble shaft, a 40 collar threaded on said shaft, said collar having a lower crowned bearing surface and a threaded portion, a socket sealed into the top of said chamber, said socket having a central aperture to receive said shaft and a mating bearing surface, a 45 gasket between said threaded portion and the wall of said socket, and a ring threaded on said threaded portion to expand said gasket for a gas-tight seal.

4. In a metallurgical furnace a rabble arm 50 mounted on a vertical rabble, a plurality of flat plate rake blades each having a hole therethrough the axis of which is disposed at an oblique angle to the axis of said rabble arm with said rabble arm received therein, spacing sleeves 55 mounted on said rabble arm between said rake blades and having surfaces at the ends thereof abutting the surfaces of said rake blades, and means securing said sleeves and said rake blades on said rabble arm.

5. In a metallurgical furnace a rabble arm 60 mounted on a vertical rabble, a plurality of flat plate rake blades each having a hole therethrough the axis of which is disposed at an oblique angle to the axis of said rabble arm with said 65 rabble arm received therein, spacing sleeves mounted on said rabble arm between said rake blades and having the ends thereof formed at an angle to abut the surfaces of said rake blades, a similar sleeve beyond the outermost rake blade, 70 and a bolt threaded into the end of said rabble arm having a head engaging the outermost end of said last mentioned sleeve whereby said rake blades and sleeves are secured on said rabble arm.

6. In a metallurgical furnace a vertical rabble 75 shaft, a collar mounted on said shaft, said col-

lar being formed from sections, means to secure said sections together and clamp said collar in any desired position on said shaft, a rabble arm mounted on each of said sections, a plurality of flat plate rake blades each having a hole therethrough the axis of which is disposed at an oblique angle to the axis of said rabble arm with said rabble arm received therein, spacing sleeves mounted on said rabble arm between said collar and the innermost rake blade, between said rake blades and beyond the outermost rake blade, 10 said spacing sleeves having the ends thereof formed at an angle to abut the surfaces of said rake blades, and a bolt threaded into the end of said rabble arm having a head engaging the outermost end of the outermost sleeve whereby said rake blades and sleeves are secured on said rabble arm.

7. In a metallurgical furnace the combination with a furnace chamber having at least one horizontally disposed sole, of a vertical rabble shaft having an enlarged portion provided with a crowned supporting bearing surface, a socket in the top of said chamber to receive said enlarged portion and having a mating bearing surface, 25 means sealing said enlarged portion in said socket in a gas-tight manner, a collar mounted on said shaft, said collar being formed from sections, means to secure said sections together and clamp said collar in any desired position on said shaft above the sole, a rabble arm mounted on each of said sections, a plurality of flat plate rake blades each having a hole therethrough the axis of which is disposed at an oblique angle to the axis of said rabble arm with said rabble arm received therein, 30 spacing sleeves mounted on said rabble arm between said collar and the innermost rake blade, between said rake blades, and beyond the outermost rake blade, said spacing sleeves having the end thereof formed at an angle to abut the surfaces of said rake blades, and a bolt threaded into the end of said rabble arm having a head engaging the outermost end of the outermost sleeve whereby said rake blades and sleeves are secured on said rabble arm.

8. In a metallurgical furnace the combination with a furnace chamber provided with a series of horizontally disposed soles alternately apertured near the center and near the periphery, of a rabble assemblage comprising a vertical rabble shaft 50 having an enlarged portion provided with a crowned supporting bearing surface, a socket in the top of said chamber to receive said enlarged portion and having a mating bearing surface, means sealing said enlarged portion in said socket in a gas-tight manner, a plurality of collars mounted on said shaft between the soles, each of said collars being formed from sections, means to secure said sections together and clamp each of said collars in any desired position on said shaft 55 above the associated sole, a rabble arm mounted on each of said sections, a plurality of flat plate rake blades each having a hole therethrough the axis of which is disposed at an oblique angle to the axis of said rabble arm received therein, spacing sleeves mounted on said rabble arm between said associated collar and the innermost rake blade on said arm, between said rake blades, and beyond the outermost rake blade on said arm, 60 said spacing sleeves having the ends thereof formed at an angle to abut the surfaces of said rake blades, a bolt threaded into the end of said rabble arm having a head engaging the outermost end of the outermost sleeve whereby said rake blades and sleeves are secured on said asso- 65 70 75

- ciated rabble arms with the rake blades disposed at angles to work ores across said soles toward the apertures therein, and a guiding bearing for said rabble shaft in the lower portion of said chamber.
5. 9. In a metallurgical furnace a charging device located in the wall of a furnace chamber adjacent the top thereof comprising a worm tube inclined downwardly and opening into said furnace chamber, a worm in said tube, a worm shaft projecting from said tube through a gas-tight bearing, a substantially vertically disposed passage opening into said tube above said worm, a hopper communicating with said passage, a pair of rotatable horizontally disposed shafts located side by side in said passage, pins on said shafts alternately positioned so that those on one shaft will pass those on the other shaft, means to rotate said shafts in opposite directions with the pins of one shaft passing downwardly on the side adjacent the compliment shaft, and means simultaneously to operate said worm shaft and said rotating means.
10. 15. In a metallurgical furnace a charging device comprising a worm tube inclined downwardly to supply powdered ore material to the furnace chamber, a worm in said tube, a worm shaft projected through a gas-tight fitting in the end of said tube and supported by bearings therein, a substantially vertically disposed passage opening into said tube above said worm, a hopper mounted on the upper end of said passage, a pair of rotatable horizontally disposed shafts located side by side in said passage, pins on said shafts alternately positioned so that those on one shaft will pass those on the other shaft, meshed gears on said shafts whereby said shafts may be operated in opposite directions, and common driving means geared to said worm shaft and to said interengaging gears whereby all of said shafts may be operated simultaneously with the pins of one horizontally disposed shaft passing downwardly on the side adjacent the compliment shaft.
20. 25. 30.
